UNITED STATES PATENT OFFICE.

WILLIAM FORD, OF ROWLESBURG, WEST VIRGINIA, ASSIGNOR OF ONE-HALF TO J. C. HOOTON, OF SAME PLACE.

DESIGN FOR A CHECK-VALVE CASING.

SPECIFICATION forming part of Design No. 27,244, dated June 22, 1897.

Application filed February 10, 1897. Serial No. 622,860. Term of patent 7 years.

To all whom it may concern:

Be it known that I, WILLIAM FORD, a citizen of the United States, residing at Rowlesburg, in the county of Preston and State of West Virginia, have invented and produced a certain new and original Design for Check-Valve Casings; and I do declare the following to be a full, clear, and exact description of the invention, such as will enable others skilled in the art to which it appertains to make and use the same.

My invention relates to a new and useful design for a check-valve casing for steam-boilers.

It relates to the entire configuration of the valve-casing.

My invention relates particularly to the design for a check-valve casing as illustrated in the accompanying drawing, in which the figure is a perspective view of a check-valve embodying my design.

The leading features of my design appear in the following description:

1 represents the oblong rectangular casing, having a threaded orifice 2. 25
3 represents the threaded nipple or pump connection, having a rectangular collar 4.
5 is a rectangular blind-cap.

Having thus fully described my design, what I claim as new and original, and desire to secure by Letters Patent of the United States, is—

The design for a check-valve casing, substantially as herein shown and described.

In testimony whereof I hereunto affix my signature in presence of two witnesses. 35

WILLIAM FORD.
